DESIGN FOR A PLAYING CARD

Lidio F. Blanco, Hillsdale, N. J., and Joseph M.
de Aragon, New York, N. Y.

Application May 4, 1939, Serial No. 85,449

Term of patent 3½ years

To all whom it may concern:

Be it known that we, Lidio F. Blanco and Joseph M. de Aragon, citizens of the United States, residing respectively at Hillsdale, county of Bergen, and State of New Jersey, and New York city, county and State of New York, have invented a new, original, and ornamental Design for Playing Cards, of which the following is a specification, reference being had to the accompanying drawing, forming part thereof.

The figure is a face view of a playing card showing our new design; the back of the card being conventional.

We claim:

The ornamental design for a playing card, as shown and described.

LIDIO F. BLANCO.
JOSEPH M. DE ARAGON.
